Related U.S. Application Data

(60) Division of application No. 29/247,396, filed on Jun. 15, 2006, now Pat. No. Des. 569,924, which is a division of application No. 29/235,734, filed on Aug. 4, 2005, now Pat. No. Des. 529,967, which is a continuation-in-part of application No. 29/223,218, filed on Feb. 9, 2005, now abandoned, and a continuation-in-part of application No. 29/233,004, filed on Jun. 24, 2005, now abandoned.

CLAIM

(51) **LOC (9) Cl.** 21-01

The ornamental design for vaned wheel parts of a toy vehicle, as shown and described.

(52) **U.S. Cl.** **D21/563**

DESCRIPTION

(58) **Field of Classification Search** D21/398, D21/548, 549, 550, 560, 561, 563, 779; D12/162, D12/214, 345; D23/411, 413; 446/164, 446/456, 462, 465, 466, 468-471, 431, 437, 446/448, 449, 451, 454-458; 180/218; 152/112, 152/165

FIG. 1 is a perspective view of a first configuration of a pair of vaned wheel parts of a toy vehicle in accordance with our new design;

See application file for complete search history.

FIG. 2 is a “front” elevation view thereof;

(56) **References Cited**

FIG. 3 is a “rear” elevation view thereof;

U.S. PATENT DOCUMENTS

FIG. 4 is an elevation view of the “right” side thereof, the elevation view of the “left” side being a mirror image thereof;

3,590,897 A * 7/1971 Bragdon 152/112
152/165

FIG. 5 is a “top” plan view thereof;

FIG. 6 is a “bottom” plan view thereof;

FIG. 7 is a perspective view of a second configuration of a pair of vaned wheel parts of a toy vehicle in accordance with our new design;

FIG. 8 is a “front” elevation view thereof;

FIG. 9 is a “rear” elevation view thereof;

FIG. 10 is an elevation view of the “right” side thereof;

FIG. 11 is an elevation view of the “left” side thereof;

FIG. 12 is a “top” plan view thereof; and,

FIG. 13 is a “bottom” plan view thereof.

The broken lines in the figures are for illustrative purposes only and form no part of the claimed design.
